UNITED STATES PATENT OFFICE.

ALBERT V. CHAMBERLIN, OF COEUR D'ALENE, IDAHO.

COIN-WRAPPER.

1,263,854.

Specification of Letters Patent. Patented Apr. 23, 1918.

Application filed November 26, 1917. Serial No. 204,051.

To all whom it may concern:

Be it known that I, ALBERT V. CHAMBERLIN, a citizen of the United States, residing at Coeur d'Alene, in the county of Kootenai and State of Idaho, have invented 5 certain new and useful Improvements in Coin-Wrappers, of which the following is a specification.

The present invention relates to improvements in coin wrappers, and is designed especially for convenience, facility, and accuracy in handling small coins. The primary object of the invention is the provision of a device that is comparatively inexpensive in 10 first cost, simple in construction and operation, and readily adaptable for use in many different ways.

The invention consists in certain novel combinations and arrangements of parts as 20 will be hereinafter set forth and claimed.

In the accompanying drawings one complete example of the physical embodiment of the invention is illustrated, made according to the best mode so far devised for 25 the practical application of the principles of the invention.

Figure 1 is a side elevation of a device embodying the invention.

Fig. 2 is a top plan view of the device, 30 partly broken away for convenience of illustration.

Fig. 3 is a vertical longitudinal sectional view of the device.

Fig. 4 is an end view of the device, showing a "roller" or friction device for wrapping the coins.

Fig. 5 is a top plan view of the device, illustrating the "roller" or wrapping device in use.

Fig. 6 is a view of the wrapper or friction device.

Fig. 7 illustrates the use of coin troughs of different sizes that may be applied to the device.

In the preferred embodiment of the invention as illustrated in the drawings, a hollow metallic base or casing 1 is used and 45 preferably provided with a felt or other soft cushion or pad 2 on its bottom, while its top 3 is slotted at 4, and provided with a pocket or depression 5 for convenience in handling the wrapped coins.

An adjustable stop member 6 passes 50 through a perforation in one end of the casing, and its stop arm 7 passes through the slot 4 in the top 3 and is located in position

to form an abutment or stop for the first coin that forms part of the series or pack of coins to be wrapped. The abutment device has a knob 8 on the end of the spring 60 stem 9 which protrudes through the notched slot 10 in the front wall of the casing, and by means of this knob, stem and notched slot, it will readily be apparent, the abutment may be adjusted within the limits of the 65 length of the slot 10, to receive coins within the trough 11.

The trough 11 is preferably of metal, and as shown, the abutment arm 7 projects through the open end of the trough sufficiently to retain the first coin therein. The trough is provided with a pair of key-hole slots 12, and the screws 13 are utilized to secure the trough in position adjacent the abutment, and between it and the depression 75 or pocket 5 in the top of the casing. At the other end of the trough, and alined with the adjustable abutment arm 7, is a spring detent 14, designed to co-act with the abutment and hold the pack of coins while being wrapped in the wrapper or paper strip W.

The longitudinally disposed spring detent 14 is fashioned with a post 15 that projects through, and is movable, longitudinally, in 85 the slot 16 in the top of the casing 1, and by means of this post, and the latch 17, the detent may be held out of operation. The latch is pivoted at 18 in the top of the casing and by means of the knob 19 may be 90 disengaged from the post, the arcuate slot 20 in the top of the casing permitting swinging movement of the latch from the outside of the casing.

Arranged parallel with the spring detent 95 14, but within the casing, is a plunger bar 21 which is connected with the post within the casing by the arm 22, and a vertical finger piece 23 projects upwardly from the plunger through the slot 24 in the casing 100 top so that the plunger may be operated from outside the casing. The plunger is guided in a perforated bracket 25, within the casing, and in addition to its function in retracting the spring detent and guiding 105 it to working position, the plunger also actuates a curved spring finger 26 to position over the wrapper as said wrapper is rotated to roll about the pack or stack of coins. This arm, which is of course located 110 outside the casing projects above from a spindle 27 revolvably supported in the cas-

- ing top, and a lever arm 28 on the spindle is connected to the plunger bar by the link 29, a spring 30 being interposed between the bracket 25 and a pin passed through the 5 plunger near the link. In Fig. 7 two additional troughs 11^a and 11^b are illustrated, of different sizes, that may be substituted for the trough 11, to accommodate different sizes and denominations of coins.
- 10 The *modus operandi* is as follows: With the spring detent 14 in position indicated in Fig. 2, the abutment arm 7 is adjusted to desired position with its free end just within the open end of the trough. A wrap- 15 per or strip of paper is then placed in the trough and the first coin is placed in the trough, on the paper resting against the abutment. Other coins are then placed in the trough, up to the desired amount, and 20 then the knob 19 is turned to free the post 15 from the latch. The spring 30 which has been under tension, forces the plunger to the left in Fig. 2 to the dotted line position so that the spring detent engages against the 25 face of the last coin and the series or pack of coins is held between the abutment arm 7 and the spring detent 14. The action of the spring plunger also swings the spring or curved finger 26 around to dotted position Fig. 2 and full line position Fig. 1 so 30 that it guides the forward edge of the wrapping paper or strip W and holds it to insure proper wrapping. To wrap the stack of coins a rolling device R is employed, 35 which has a friction belt or contact face that is rolled or passed over the top or upper face of the wrapper, as in Fig. 5, and with the result that the pack of coins is revolved and the wrapper rolled upon itself to form 40 a compact and smooth wrapper about the coins. The spring detent is now withdrawn by pressure on the finger piece 23, and this action also swings the curved guide finger to inoperative position.
- 45 The right end of the wrapper may now be turned over the coins, the depression or pocket 5 allowing room for the fingers during this operation, and the abutment holding the pack of coins at the other end until 50 the operation is completed. Then the pack may be taken from the trough and the other end have its edges folded over to complete the wrapping. In this manner a neat, smooth, and compact stack of coins is

wrapped and ready for final disposition as 55 desired. While it is preferred that the rolling device be employed to wrap the paper about the stack of coins, it will be apparent that this may be done also by passing the fingers and palm of the hand over the paper 60 and coins if desired, and the use of the wrapping or rolling device be omitted.

Claims:

1. The combination in a coin wrapping device with a trough containing a wrapper, 65 an abutment at one end of the trough, and a movable detent alined with the abutment at the other end of the trough whereby the coins may be wrapped while held between the abutment and detent means for withdrawing the detent, and a guide for the wrapper connected to said means whereby the guide and detent may be moved to inoperative position.

2. The combination in a coin wrapping 75 device with a trough containing a wrapper, an abutment at one end of the trough, and a movable detent at the other end of the trough alined with the abutment, means for moving the detent, and a guide finger for 80 the wrapper operatively connected with said means whereby the detent and finger may be moved to inoperative position synchronously.

3. The combination in a coin wrapping 85 device with a trough containing a wrapper, an abutment at one end of the trough, and a movable detent at the other end of the trough alined with the abutment, a holding latch for the detent, a spring pressed 90 plunger connected with the detent, and a guide finger for the wrapper operatively connected with the spring pressed plunger whereby the detent and finger may be moved to inoperative position synchronously. 95

4. The combination in a coin wrapping device with a trough containing a wrapper, an adjustable abutment, a movable detent and a holding latch therefor, a spring pressed plunger connected with the detent, 100 a spindle and guide finger thereon for the wrapper, and connections between the spindle and plunger whereby the detent and finger may be moved synchronously, to inoperative position.

In testimony whereof I affix my signature.

ALBERT V. CHAMBERLIN.
